DEFLECTING DEVICE FOR BRAUN TUBES

Ernst Ruska, Berlin-Zehlendorf, Germany, assignor to the firm of Fernseh Aktiengesellschaft, Zehlendorf, near Berlin, Germany

Application December 6, 1935, Serial No. 53,264
In Germany December 12, 1934

4 Claims. (Cl. 250—159)

This invention relates to deflecting plates for Braun tubes.

To increase sensitivity it is known to curve the deflecting plates of Braun tubes in the longitudinal direction thereof or in the direction of the undeflected ray, so that the electrons of the bundle to be deflected entering at the edge of a deflecting plate flow along the curve of the plate at maximum deflecting tension.

According to the invention, whether parallel, inclined or curved, the plates are curved along their breadth, i. e., transversely to the direction of the ray, in such a way that the two plates forming a pair have a concave or convex form relative to the ray.

The first result of this construction with respect to pairs of plates on which the undeflected ray falls and which form the first deflecting system is a local sensitiveness varying somewhat with the deflection. This due to the fact that in the planes disposed vertically to the ray the lines of force do not extend parallel any more but, owing to vertical emergence from both plates, either bulge in the middle plane or converge, according to the curvature of the plates. The deflected ray passes through a stronger or weaker transverse field than the undeflected ray in the center. Only at the plate entrance the cross section of the ray simultaneously extends over the middle and marginal field if the distance of the plate entrance is equal to the diameter of the ray at this point. Due to the bulging of the lines of force, the local sensitiveness of plates that are convex relative to the ray is slightly lower when the ray is at rest than in case of a deflected ray, whereas concave plates inversely disclose a somewhat lower marginal sensitiveness.

Such intentional variation in sensitiveness is required chiefly for two reasons.

In the first place, variation in sensitiveness of this kind permits compensation of the usually not strictly linear saw-tooth voltage with respect to deflection. Since sweep circuits are much cheaper and simpler if strict linearity can be dispensed with and lateral curving of the plates practically does not involve extra expenditure, an essential technical advantage is gained.

A further reason for lateral curving of the plates to insure very wide-angled deflection, which is desirable with respect to short tube length, is that the geometrical conditions alone demand a somewhat variable angular sensitiveness (angular deflection: deflecting voltage). It is

not the line or point spacing over the picture, measured along the curved fluorescent screen, that is to be constant but the projection thereof upon the plane extending perpendicularly to the axis of the tube. Quantitatively, conditions are such that practically in the most important instances the radius of the screen is equal to or greater than the distance of the deflecting system from the screen. The deflecting sensitivity must then decrease outwardly in order to produce points or lines of uniform relative spacing on the screen and particularly on the plane disposed vertically to the axis of the tube. The deviation from the constancy of sensitivity due to the geometrical conditions in wide angle deflecting systems mitigates therefore the effect of a not strictly linear saw-tooth voltage upon the image geometry, as the increase thereof in time decreases somewhat with the voltage.

The radius of curvature is selected according to the relative plate distance and the voltage to be compensated or the geometrical conditions, though it need not be constant over the plate length. It is frequently preferable to refrain from curving the entrance edge of the plate system and to increase the curvature only gradually towards the outlet edge. This is particularly necessary in case of plates upon which the ray is incident while it is still undeflected and if the spacing of the entering edges corresponds to the diameter of the ray.

By way of example, the invention is diagrammatically illustrated in the accompanying drawing, in which Figures 1, 2, and 3 are plan, vertical and end views respectively of one pair of deflecting plates.

Figures 4, 5 and 6 are plan, vertical and end views of a second pair of deflecting plates.

Figure 7 is a view of a cathode ray tube in section with both pairs of deflecting plates positioned therein.

Referring to the drawing, and first to Fig. 1, a pair of deflecting plates referred to in the preceding last paragraph of the general description is designated 1, 2. The strength of the transverse field is to be as constant as possible over the ray section itself. When deflected the ray comes out of central position only in the course of the plate length and, without too much variation in the field strength over the ray section, passes according to the amount of its deflection through fields of varying intensity, whereby variation in sensitivity is insured.

A second and different variation in sensitiveness with respect to plates curved along their broad-

side prevails in regard to the pair of plates serving as second deflecting system. Upon such a pair the ray, depending upon the degree of the first magnetic or electric deflection, is incident 5 at different angles, and by a suitable curvature a different means sensitivity, i. e., extending over the entire angular range, of the pair of plates concerned can be attained as a function of the deflection by the first system. This variation 10 in sensitivity is particularly necessary in the wide angle first deflecting system and usually consists in keeping constant the sensitivity relative to the course thereof which in non-curved plates is determined by the beam paths differing in 15 length according to the angle of incidence.

It is advisable to form the plates of such a pair as sectors of a surface of rotation with the plates inclined, e. g., from a cone surface. Figs. 4, 5 and 6 show such sectors designated 3, 4 the cones 20 of which lie with their axes vertically to the axis of the ray, the limitation of the plates on the entering side being formed by the intersection of a plane parallel to the axis of the tube with the cone. The axis of the cone preferably extends 25 through the pivot of the first deflecting system, so that the radius of the intersection is equal to the distance of the entering edge from the pivot of the first deflecting system. The leaving edge also develops as intersection of a 30 parallel plane with the sector of the cone surface. The advantage afforded by such plates is that the ray always enters and leaves vertically to the edge of the plate. A section A—B in a 35 plane vertically to the direction of the ray shows in Fig. 6 the curvature of the plate.

If plate-like electrodes are used besides the deflecting plates proper, they are also preferably formed from corresponding surfaces of rotation, the projection thereof ensuing as continuation

of the vanishing line of the plate. In longitudinally curved plates the meridian section of the solid of rotation appears as a curve having a decreasing bend.

Fig. 7 shows the relative position of the two 5 deflecting systems according to Figs. 1 to 6, inclusive. Each deflecting system can be provided with counter-electrodes on the entering and emerging side.

I claim:

1. An electrostatic ray deflecting device for a cathode ray tube, consisting of two deflecting plates having each a convex curvature relative to the undeflected ray axis of said tube as defined by cross-sectional planes perpendicular to said 15 axis.

2. In a cathode ray tube, an electrostatic ray deflecting device, consisting of two deflecting plates having opposed convex curvatures of different radii of curvature relative to the undeflected ray axis of said tube as defined by cross-sectional planes perpendicular to said axis. 20

3. An electron beam deflecting device for a cathode ray tube, comprising plates having each a convex curvature relative to the undeviated 25 cathode ray axis of said tube, as defined by cross-sectional planes perpendicular to said axis, said plates having a changing radius of curvature along their length.

4. An electrostatic ray deflecting device for a cathode ray tube having therein cathode ray beam producing means, consisting of two deflecting plates of opposed convex curvature relative to the undeflected ray axis of said tube in a plane perpendicular to said axis, said plates having straight edges on the side thereof toward said beam producing means. 30

ERNST RUSKA.
